Primary Examiner — Darlington Ly

(74) Attorney, Agent, or Firm — Reinhart Boerner Van Deuren P.C.

(57) **CLAIM**

The ornamental design for a right angle driver, as shown and described.

DESCRIPTION

FIG. 1 is a front and left side perspective view of a right angle drive showing my new design with a chuck and handle bar attached;

FIG. 2 is a front and left side perspective view of the right angle drive shown in FIG. 1 without the chuck and handle bar attachments;

FIG. 3 is a left side elevation view thereof;

FIG. 4 is a rear elevation view thereof;

FIG. 5 is a front elevation view thereof;

FIG. 6 is a right side elevation view thereof;

FIG. 7 is a bottom plan view thereof; and,

FIG. 8 is a top plan view thereof.

The broken lines showing the chuck, handlebar, shank and other features of the right angle driver are provided for the purposes of illustrating portions of the article and form no part of the claimed design. Additionally, the dash-dot broken lines illustrate boundaries between portions of the article that form the claimed design and the portions that do not.

1 Claim, 7 Drawing Sheets
